H. AIKEN.
LAMP SOCKET.
APPLICATION FILED SEPT. 3, 1913.

1,144,956.

Patented June 29, 1915.

UNITED STATES PATENT OFFICE.

HERRICK AIKEN, OF LAWRENCE, MASSACHUSETTS, ASSIGNEE, BY MESNE ASSIGNMENTS, TO AIKEN LAMP COMPANY, OF FRANKLIN, NEW HAMPSHIRE.

LAMP-SOCKET.

1,144,956.

Specification of Letters Patent. Patented June 29, 1915.

Application filed September 3, 1913. Serial No. 787,998.

To all whom it may concern:

Be it known that I, HERRICK AIKEN, a citizen of the United States, residing at Lawrence, in the county of Essex and State 5 of Massachusetts, have invented a new and useful Lamp-Socket, of which the following is a specification.

This invention relates to a lamp support capable of general use, but particularly 10 adapted for use on automobiles and the like. It is an improvement on an invention made by James C. Ramsey, Jr., an application for patent on which was filed Oct. 31, 1912, Serial No. 728,821.

15 The principal object of the invention is to provide a simple and inexpensive construction for this purpose involving parts which can be separated readily when desired and including details of construction 20 by which the lamp and the frame which carries it can be swung through angles about different axes and by which they will remain in any position without the use of separate fastening devices.

25 Further objects and advantages of the invention will appear hereinafter.

Reference is to be had to the accompanying drawings, in which—

30 Figure 1 is a side view of a portion of an automobile showing a preferred embodiment of this invention applied thereto; Fig. 2 is a side view of the lamp and its frame on enlarged scale showing the parts in central longitudinal section; and Fig. 3 is a 35 sectional view on the line 3—3 of Fig. 2.

The parts are supported on a stand 10 which has a vertical part and a cylindrical horizontal arm 11. This horizontal arm is 40 provided with a conical end 12 and with an integral collar 13 at the end of the cone.

45 The frame 15 for the lamp is provided with a hollow, externally screw-threaded projection 16 and with a socket 17 fitting the end 12 and receiving it. At right angles thereto it is provided with another screw-threaded projection 18 having a cylindrical passage 19 therethrough. This 50 frame also is provided with a vertical conical extension 20 at the top. This has a central passage 21 therethrough.

For the purpose of holding the frame 15 on the stand 10 a nut 23 is provided adapted to be screwed on the threaded end 16 and having an end flange coming down behind the collar 13. An expandable spring

24 is provided between this flange and the collar to normally hold the frame up as far as possible on the conical end 12.

Through the passage 19 extends a hollow shaft 26 and fitting the passage frictionally so that it will remain in any position to which it is turned. It has a collar 27 thereon, and a nut 28 is provided for holding this in position in the frame. A hollow sheet metal rod 29 fits the projecting end 35 of the shaft 26 and has a loose fit in the end of the nut 28. This sheet metal rod is therefore capable of turning the shaft 26 when it itself is turned. On the end it is provided with a handle 30 and with a pair 70 of push buttons 31.

On the inner end of the shaft 26 is splined a bevel gear 32. This meshes with a bevel gear 33 on the inner end of a hollow shaft 34 which extends through the passage 21. 75 On the top of this shaft 34 is screwed a hub 35 forming a part of the lamp body 36. A nut 37 is shown for securing these in position.

The wires for the lamp designated *a* and *b* 80 come up through the hollow stand 10 and one of them, as *b*, passes directly up through the hollow shaft 34 to the lamp *c*. The other one *a* passes in through the arm 11 along the interior of the hollow shaft 26 and rod 27 to 85 the push buttons 31, then back again into the interior of the frame 15 and up through the shaft 34 to the other terminal of the lamp. The push buttons, by means well understood in the art, are designed to connect 90 and disconnect the two parts of the wire *a* so as to control the lighting of the lamp. In this way it will be seen that the operator having control of the handle 30 can turn the current on and off very readily and also 95 twist the handle about its own axis to turn the lamp about a vertical axis when the parts are in the position shown in the drawing. He can also swing the whole handle and frame about the axis of the arm 11. 100

Although I have illustrated and described only a single embodiment of the invention I am aware of the fact that many modifications can be made therein by any person skilled in the art without departing from 105 the scope of the invention as expressed in the claims. Therefore, I do not wish to be limited in these respects, but

What I do claim is:

1. The combination with a stand having a 110

horizontal, cylindrical arm provided with a conical end, of a lamp supporting frame provided with a socket fitting said conical end, and yielding means for forcing the frame along the conical end toward the cylindrical part.

2. The combination with a fixed support having a conical end and a stationary collar at the large end of the cone, of a frame having a socket for receiving said conical end, and a screw-thread on the exterior, a nut connected with said threads and extending beyond said collar, and a spring located between the collar and the end of the nut.

15 3. The combination with a stand having a horizontal, cylindrical arm provided with a conical end, of a lamp supporting frame provided with a socket fitting said conical end, and having a conical projection, and a lamp body provided with a conical socket for receiving said projection whereby the frame is held frictionally on the support and the lamp body is capable of being turned thereon on a different axis.

25 4. The combination with a support having a horizontal arm thereon, of a frame

frictionally held on said arm and capable of turning about the axis of the arm, a lamp body connected with said frame and capable of turning on an axis at right angles to the first named axis, and means extending through said frame for turning the lamp body on its axis.

5. The combination with a support having a horizontal arm thereon, of a frame frictionally held on said arm and capable of turning about the axis of the arm, a lamp body connected with said frame and capable of turning on an axis at right angles to the first named axis, and means extending through said frame at right angles to both of said axes for turning the lamp body on its axis, and holding it frictionally in its adjusted positions.

In testimony whereof I have hereunto set my hand, in the presence of two subscribing witnesses.

HERRICK AIKEN.
